ATTORNEY.

UNITED STATES PATENT OFFICE.

MILTON D. THOMPSON, OF FAIRHAVEN, MASSACHUSETTS.

PROPELLER.

Application filed March 14, 1925. Serial No. 15,618.

My invention relates to propeller wheels and more especially to that type of wheel in which the blades, when not revolving with the shaft, may feather or turn on their axes a certain amount.

This type of wheel is quite largely used on sail craft equipped with auxiliary motor driven propulsion and is extremely valuable in case the sails are used as the propelling agent.

In feathering the blades, their sharp entering edges cut the water in a plane coincident with that of the direction of travel of the boat or ship and therefore do not offer a large amount of resistance to the movement of the latter when under sail power.

In some types of feathering propeller wheels a tube or sleeve is employed to actuate the blades in bringing them into feathering position. This sleeve encases the shaft, extends from the propeller inboard and is operated by a lever or screw arrangement.

This style of construction necessitates a certain amount of complication in the mechanism and its operation is often attended with more or less difficulties, requires constant attention and frequent repairs, which, on account of the inaccessibility of the parts, are quite apt to be expensive.

One of the principal objects of my invention is to provide a feathering blade which is automatic in its action,—requiring no outside mechanical devices to bring it into the feathering position,—depending wholly on the force of the water against the rearward portion of the blade to produce the result.

Another object is to eliminate many of the parts required in the sleeve or positively operated types. In doing this I am enabled to make a much stronger propeller, insuring longer life and fewer replacements. It will also relieve the engineer of the craft of all care or thought relative to the feathering of the blades, as immediately upon stopping his motor the blades automatically adjust themselves to the fore and aft, or feathering position.

Other objects of my invention will be apparent from a consideration of the detailed description hereinafter found in my specification when taken in connection with the accompanying drawing wherein a preferable embodiment of my invention is shown and

in which like characters of reference refer to similar parts in all of the several views.

In the drawings:—

Fig. 1, is a view, in perspective, of my three-blade feathering propeller wheel;

Fig. 2 is a view, in perspective, of one of the blades;

Fig. 3 is a view, in perspective, of the cam sleeve;

Fig. 4 is a view, in perspective, of the cam ring;

Fig. 5 is a view, in perspective, of the forward part of the casing;

Fig. 6 is a view, in perspective, of the rearward of aft part of the casing;

Fig. 7 is a transverse sectional view, taken on line 7—7, Fig. 8;

Fig. 8 is a longitudinal sectional elevation, showing some parts in full, and taken on a central line through the casing, as on line 8—8, Fig. 7;

Fig. 9 is a view representing the blade in ahead and astern positions in full lines, and in feathering position in dot and dash lines; and

Figs. 10 and 11 are diagrammatical illustrations showing the effect of changing the pitch angles of the blades.

Referring to the drawings, 1 is the propeller shaft, 2 is a blade, 3 is the hub of the blade and 4 is a scored recess in the hub.

Eccentrically positioned on the end of this hub (3) of the blade is a pintle 5.

Fixed on the shaft 1 is the cam sleeve 6 having cut therein a groove or path 7. This cam path starts at the after end of the sleeve (6) and is parallel to the axis of the shaft for a spaced distance when it bifurcates into two spirally cut grooves or fin-ways, one right hand and the other left hand. There are two sets of these paths on the periphery of the sleeve (6), placed diametrically opposite each other. The diameter of the forward end of the sleeve, at 6' is somewhat enlarged, and the opposite end at 6'' is reduced, relative to the diameter of the central portion thereof.

Loosely mounted over the central portion of the cam sleeve 6 is a cam ring 8, which is adapted to not only slide longitudinally of the sleeve but to oscillate thereon a predetermined amount. This combined movement of the cam ring (8) is produced by the engagement of the cam path with the pins 9

and occurs whenever the shaft starts to rotate in either direction. Equally spaced about the outer circumference of the cam ring 8 are depressions 10 in which the pintle 5 operates.

In Figs. 5 and 6 are shown the forward and aft portions respectively of the casing, 11 representing the former and 12 the latter. These two members, 11 and 12, are joined,—the joint being transversely of the axis of the shaft, and make when together a shell of substantially spherical shape. Ears 12' projecting outwardly from the part 12 enter the part 11 and by means of the screws 13 secure one part to the other.

On the periphery of the shell, and centrally of the joint line, are apertures 14 in which operate and are secured the hubs of the blades, the thickness of the shell at these openings being such as to fill the recess 4 in the hub 3 of the blade and allows the latter to oscillate therein at certain times, but prevents its withdrawal from the casing.

Abutting the reduced end of the sleeve 6, at '6", is a collar 15 made somewhat larger than the portion 6". The nut 16 on the rearward end of the shaft 1 secures this collar (15) as well as the sleeve 6 rigidly on the shaft. A circumferential recess is thus formed on the aft end of the sleeve 6 and this operates the internal collared portion 17 of the threaded thrust bushing 18,—the latter being screwed into the portion 12 of the casing and providing means for securing the conical cap 19 to the casing. It will be seen that this collared portion 17 is the element which controls and locates the position, longitudinally on the shaft, of the casing or shell part of the propeller upon the sleeve 6. Another function of this collar, and the threaded bushing, of which this collar is a part, with its capacity for longitudinal adjustment in and out of the casing, will hereinafter be disclosed.

As I have previously stated in my preamble, the blades of my propeller are capable of feathering automatically. By reference to Figs. 8 and 9, and the following explanation, it will be apparent how this result is accomplished.

In the first place let us assume that the blades are in the feathering position and the shaft 1 is to rotate in a right-handed direction,—or as indicated by the arrow in full lines in Fig. 8,—and that we are employing a right-handed blade relative to its pitch angle. Then as the cam sleeve 6 is fixed on the shaft 1, the rotation of the latter combined with the resistance of the water against the working of the blade will result in oscillating it on its axis and bringing the pins 9 to the terminus of the cam path 7, or at the point marked "b" in Figs. 3 and 8, with the blade positioned, in relation to its pitch angle, as seen at "x—x", Fig. 9. The

engagement of the pintles 5 by the sides of the depressions 10 is the immediate cause of the changing of the blades from "feathering" to "ahead" position, the action being comparable to that of a connecting rod on a crank-pin,—the latter representing the pintle 5 and the former the sides of the depression 10.

If the rotation of the shaft 1 is continued in the right-handed direction the pins 9 will remain in the ends of the path 7, at "b", and the craft will be propelled in a forward direction.

Immediately on stopping the motor, however, which will cause the shaft 1 and the cam sleeve 6 to remain stationary, the resistance of the water against the back side of the blades, as the craft still has headway, will cause them to oscillate on their axes, and the pintles 5 to swing the cam ring 8 backwardly on the sleeve 6 bringing the pins 9 again into the junction of the two spiral grooves or paths 7, as at "c". The blade now assumes the position it was in at the start, or feathering, as seen at "y—y", Fig. 9, and it will remain thus until some further rotation of the shaft 1 takes place.

Before passing to the next step in the operation of the propeller it might be well to state that the blades of my propeller wheel are of the so-called "unbalanced" type,—in other words,—there is more surface contact with the water on the aft or rearward side of their axes than on the forward side, so that when the shaft is idling and the craft "under way" the resistance of the water against the blades will straighten them out, much as the tail of a weather vane will bring the whole vane into a direction corresponding to that from which the wind is blowing.

Thus far I have described the actuation and positions of the blades in feathering and "go ahead" positions, and have made clear, also, that whenever the motor stops the blades will come into feathering position.

Starting again from this latter position, and driving the shaft 1 in the opposite or astern direction as indicated by the arrow in dotted lines, Fig. 8, the first action is of the cam sleeve 6 oscillating in the casing sufficiently to bring the pins 9 into the terminals of the right-hand spiral portions of the path 7. This will move the cam ring 8 forwardly on the sleeve 6 and swing the blades into the same positions, relative to their pitch angles, as obtained when the shaft was rotating to cause a forward movement of the craft, and all parts will be in identically the same position, longitudinally of the shaft,—the only difference in the "go ahead" and "go astern" positions is that the pins 9 are at the points "b" in the former and the points "a" in the latter.

In order to key the cam ring 8 to the cas-

ing 12 and cause them to oscillate in unison over the sleeve 6, I provide grooves 20, on the ring, which act as key-ways, and make projections 21 on the ears, 12' of the casing 12 to fit these grooves and act as keys. This does not, however, prevent the ring reciprocating freely in the casing and along the surface of the sleeve 6.

Reverting to a consideration of the function of the threaded bushing 18 it will be seen by viewing the different figures in the drawing that the pins 9 and the pintles 5 are at all times in the same plane, transversely of the shaft 1.

It will also be apparent that the terminal points *a* and *b* in the path 7 mark the extreme movements, in one longitudinal direction, of the pins 9 at any and all pitch angles of the blades. This establishes a distance, variable in different pitch angles of the blades, between two planes running transversely of the shaft 1,—one plane cutting the axis of the hub of the blade 2 and the other axis of the pindle 5. Now the movement of the cam ring 8 along the sleeve 6 acts to move the pintles 5, held in the depressions 10 of the ring, in an arc,—the axes of the blade hubs 3 oscillating in the apertures 14 of the casing, being the center of turning point.

Therefore when the threaded bushing 18 is screwed into or out of the casing member 12, this distance, just mentioned, between the two planes becomes changed and has the effect of lengthening or shortening, respectively, the action of the pintles 5, resulting in producing a finer or coarser pitch angle to the blades 2.

At any pitch angle of the propeller, and with the craft being moved thereby either forwardly or backwardly, the pins 9 will come to a seat in the terminal points of the path 7, at either *b* or *a*, respectively, and to allow proper clearance for these pins (9) when the blade is feathering and a fine pitch angle is employed the junction of the two branches of the path, at *c*, is made somewhat elongated.

In Figs. 10 and 11 I have shown, diagrammatically, the resulting change of angles of pitch of the blades with a change of location of the threaded bushing 18. In the former figure (10) the bushing has been screwed further into the casing 12, resulting in a larger arc of action *m* for the pindle 5 and allowing the blade to come to a finer pitch angle *n*. In Fig. 11 the reverse takes place by screwing the bushing out of the casing a certain amount.

I have illustrated my propeller as of the three-bladed type, but it is very apparent that a greater or less number, as four or two might be employed with equal facility.

And while I preferably choose to construct the parts as illustrated and described,

I elect, and shall consider myself at liberty to depart from the exact mechanical details as herein portrayed, provided, however that any such changes shall not depart from the spirit and intent of the invention and fall within the scope of the appended claims.

I claim:—

1. In a feathering and reversing propeller, the combination, of a shaft, a hub fixed on said shaft, a pin-way on said hub, starting at the after end thereof and diverging into two pin-ways, one spiralling to the right hand and the other to the left hand, a cam-ring mounted on said hub and adapted to both oscillate and reciprocate thereon, pins on the inner periphery of said cam-ring, adapted to be engaged by said pin-ways, a transversely jointed casing, the forward part bearing on an enlarged portion of said hub, bearings equally spaced about the periphery of said casing, propeller blades oscillatively operable in the said bearings and with hubs having circumferential grooves, the collars thus formed being,—the one on the inner and the other on the outer side of said casing, pins eccentrically placed and inwardly disposed on the ends of said propeller hubs, slots on the outer periphery of said cam-ring, their sides adapted to engage said pins in said propeller hubs and means for securing said casing against longitudinal movement on said shaft.

2. In a feathering and reversing propeller, consisting of a shaft, a hub fixed on said shaft, a two-part casing surrounding said hub, peripheral bearings on said casing, their centers co-incident with the joint line of the latter, propeller blades oscillatively mounted in said bearings, pins eccentrically placed on and projecting inwardly from the hubs of said propeller blades, a cam-ring mounted over said shaft hub and susceptible of both a reciprocatory and oscillatory movement thereon, pin-ways on the periphery of said cam-ring adapted to engage the pins in said propeller blade hubs, means to actuate said cam-ring and means to secure said casing in various positions, longitudinally, on said shaft hub, whereby the distance between the transverse planes cutting the centers of the propeller blade hubs, may be varied for the purpose of changing the pitch angles of said propeller blades.

3. In a propeller, the combination of a shaft, a shaft hub fixed to said shaft, a diverging pin-way on said hub with its apex rearwardly disposed, a cam-ring mounted over said hub, pins on the inner periphery of said cam-ring adapted to operate in and to be engaged by the said diverging pin-way, a two-part casing oscillatively mounted on said shaft hub, means for keying said cam ring and said casing together whereby they may oscillate in unison but be independent in their longitudinal movements, bearings

on the periphery of said casing, propeller blades mounted in said bearings, means to oscillate said propeller blades in said bearings, means to locate said casing in various and predetermined positions axially of and along the said shaft hub, and a conical cap adapted to serve as covering means for the end of said shaft and a check for said casing.

4. A feathering and reversing propeller comprising, in combination, a rotatable shaft; a casing carried by said shaft; propeller blades oscillatively mounted on said casing for movement between propelling position and feathering position; a cam-ring mounted on said shaft within the casing and movable longitudinally along said shaft; operative connection between said cam-ring and said blades whereby the blades are oscillated upon longitudinal movement of said cam-ring; and operative connection between

5. A feathering and reversing propeller, comprising, in combination, a rotatable shaft; a casing carried thereby and adjustable therealong; propeller blades oscillatively mounted on said casing for movement between propelling position and feathering position; means operatively connecting said shaft and said blades whereby upon rotation of said shaft the said blades are oscillated into propelling position; and means for adjusting the position of said casing along said shaft whereby the operation of said connecting means is varied to effect different angular settings of the blades with respect to their axis of oscillation.

MILTON D. THOMPSON.
